(57) **CLAIM**

The ornamental design for a leukocytes detector for medical purpose, as shown and described.

DESCRIPTION

FIG. 1 is a top perspective view of a leukocytes detector for medical purpose;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof; and,

FIG. 8 is another perspective view thereof, wherein a transparent cover is in an open position.
